UNITED STATES PATENT OFFICE.

WILLIAM S. ROBBINS, OF NEW BEDFORD, MASSACHUSETTS.

DESIGN FOR HARNESS ORNAMENTS.

Specification forming part of Design No. 9,292, dated May 16, 1876; application filed April 11, 1876.
[Term of Patent 3½ years.]

To all whom it may concern:

Be it known that I, WM. S. ROBBINS, of New Bedford, in the county of Bristol and State of Massachusetts, have invented a Design for an Ornament for Harnesses of Horses, of which the following is a specification:

The nature of my design is fully represented in the accompanying photographic illustration, to which reference is made.

A represents a glass ornament, cut in facets and hung between the arms of the frame B, in such manner that it may swing freely, which frame may be affixed to the harness of a horse in the usual manner.

I am aware that swinging ornaments are

used on harnesses, and that cut-glass ornaments are used for other purposes, and I do not claim them. The distinctive character of my design is in the application of cut-glass brilliants for ornamenting harnesses.

I claim as my invention—

The design for harness ornaments, consisting of the bell-shape frame B, provided with a glass pendant, A, cut with facets, substantially as shown and described.

WILLIAM S. ROBBINS.
